UNITED STATES PATENT OFFICE.

JOHN KIRSCHBAUM, OF WATERBURY, CONNECTICUT, ASSIGNOR TO ALAN ROBB FERGUSSON, OF NEW YORK, N. Y.

CLAMP.

SPECIFICATION forming part of Letters Patent No. 743,646, dated November 10, 1903.

Application filed September 26, 1902. Serial No. 124,913. (No model.)

To all whom it may concern:

Be it known that I, JOHN KIRSCHBAUM, a citizen of the United States, residing in Waterbury, in the county of New Haven and State of Connecticut, have invented certain new and useful Improvements in Clamps, of which the following is a specification.

The present invention refers to clamps such as used for clamping supports for various purposes to the shelves or partitions of desks, especially roll-top desks. It is known in devices of this kind to hold together the clamping members by means of a sliding collar or ring or by means of a screw and nut, the screw-bolt being secured to one member and the nut bearing against the other of the members. Either of these devices shows grave defects, consisting particularly in the facts that the top of the supporting shelf or board is obstructed by part of the clamp, that the collar in one case is not easy of adjustment, and the screw in the other case must be of considerable length to allow the application of the device to shelves or boards of greatly-varying thickness.

The underlying invention is adapted for use on boards or shelves of practically any desired thickness and leaves the top of the board substantially clear and unobstructed.

The accompanying drawings, forming part of the present application, show the new device in its preferred form, the essential of which consists in the employment of a rotary spiral member adapted to draw together the clamping means of the device and adjust the same to varying thicknesses of the supporting board or shelf.

Figure 1 is a side elevation of the device; Fig. 2, a view of the lower side of the same; and Fig. 3 a view similar to that of Fig. 1, showing the device clamped to a board or shelf.

1 in Fig. 1 is the top plate of the device forming the stationary clamping member and is provided with a longitudinal slot surrounded by turned-up ribs 2. This plate is bent substantially at right angles, as at 3, forming the base for a lamp-staff or other device, as hereinafter will be described more fully.

50 The end of this bent part 3 is provided with bearings for a pivot 4 of the movable clamp-

ing member. Stationary member 1 is furthermore provided with a bracket 5, forming a bearing for the pivot 6 of a rotary operating member 7. This member consists of a flat disk having a preferably milled circumference and extending somewhat above the opening in plate 1, Fig. 1, surrounded by the ribs 2, is provided on one side with a spiral rib 8, forming a spiral groove in which is located a projection or lug 12, formed in the slot 11 of the movable clamping member 9. This clamping member is pivoted to the stationary clamping member, as at 4, is provided with ribs 10, similar to ribs 2 on stationary member 1, and carries at its free end 13 an adjustable clamping-plate 15, pivoted to 13 by means of a bearing-bracket 14.

The base portion of the stationary member carries any suitable translating device or, for instance, a lamp-bracket consisting of a staff 16, a ball-and-socket joint 17, having a screw-threaded member 18 for holding a fixture, &c.

By suitably modifying the free ends of the clamping members the device may be used for various purposes.

The operation of the device is as follows: The disk 7 is rotated until the stud 12 is located in the outermost groove of the disk. Then the stationary member 1 is placed on top of the supporting-board 19, and by now turning the disk 7 in the opposite direction the stud 12 will glide in the grooves formed by the spiral rib 8 and be drawn more and more toward the center of the disk 7, whereby plate 15 will adjust itself to the lower side of the supporting-board 19 until it rests against the same. For loosening the clamp it is only necessary to turn the disk 7 so as to bring stud 12 away from the center of the disk.

Having now described the invention, that which is considered new and useful, and desired to be secured by Letters Patent, is—

1. A desk-clamp, comprising a plurality of clamping-arms, supporting means for a translating device on one of the arms, a spiral engaging device between the arms, and a self-adjusting holding-plate on the other of the arms.

2. A clamp, comprising a stationary arm carrying a rotatable disk having a spiral-

shaped rib thereon, and a movable arm carried by the stationary arm and having a stud engaged by said rib so that rotation of the disk varies the distance between the free ends of the arms.

3. In a desk-clamp, the combination with a stationary arm, of a movable arm pivoted thereto, a rotatable disk on said stationary arm and having a spiral rib, a stud on said movable arm adapted to be engaged by the spiral rib, and means on said stationary arm for carrying a translating device.

4. The combination with a plurality of pivoted members, of a spiral rotatable in its own plane and carried by one of the members, and engaging means for said spiral on the other of the members.

5. The combination with a stationary arm and a movable arm pivoted thereto, of a spiral member on the stationary arm and rotatable in its own plane, and engaging means for said spiral secured to the movable arm.

6. A clamp comprising two clamping members, a spiral on one of the members rotatable in its own plane and adapted to engage with the other member and to vary the distance between the members.

7. A desk-clamp, comprising a plurality of clamping members, a spiral engaging means for and between the members, and a self-adjusting holding-plate on one of the members.

8. A desk-clamp, comprising a stationary member, a movable member pivoted thereto, rotatable means secured to said stationary member and having a spiral rib, and engaging means on said movable member for said spiral rib.

In testimony whereof I have hereunto set my hand, in the presence of two subscribing witnesses, this 24th day of September, 1902.

JOHN KIRSCHBAUM.
